UNITED STATES PATENT OFFICE.

ROY X. TUTTLE, OF BATTLE CREEK, MICHIGAN, ASSIGNOR TO THE GOOD HEALTH PUBLISHING CO., OF BATTLE CREEK, MICHIGAN.

ELECTRIC-LIGHT BATH OR TREATMENT APPARATUS.

1,059,505.

Specification of Letters Patent.

Patented Apr. 22, 1913.

Application filed September 13, 1911. Serial No. 649,164.

To all whom it may concern:

Be it known that I, ROY X. TUTTLE, a citizen of the United States, residing at the city of Battle Creek, county of Calhoun, and State of Michigan, have invented certain new and useful Improvements in Electric-Light Bath or Treatment Apparatus, of which the following is a specification.

This invention relates to improvements in electric light bath or treatment apparatus.

The main objects of this invention are: first, to provide an improved electric light bath or treatment apparatus adapted for use in connection with a common bath tub. Second, to provide an improved electric light bath or treatment apparatus which may be collapsed into a compact form when not in use and one which may be quickly erected and adjusted for use or collapsed.

Third, to provide an improved electric bath or treatment apparatus which is simple and economical in structure, and at the same time, one which is not likely to get out of repair in use.

Further objects, and objects relating to structural details will definitely appear from the detailed description to follow.

I accomplish the objects of my invention by the devices and means described in the following specification.

The invention is clearly defined and pointed out in the claims.

A structure which is a preferred embodiment of my invention is clearly illustrated in the accompanying drawing, forming a part of this specification, in which:

Figure I is a perspective view of a structure embodying the features of my invention, it being shown in operative relation to a bath tub, a portion only of the bath tub being shown. Fig. II is an enlarged detail end view of the structure appearing in Fig. I. Fig. III is a vertical central section taken on a line corresponding to line 3—3 of Fig. II, the seat being shown in full lines. Fig. IV is a detail plan view with the covering or wall 28 omitted. Fig. V is a detail plan view of the seat supporting bar. Fig. VI is a detail section taken on a line corresponding to the broken line 6—6 of Fig. V. Fig. VII is an end view of the structure collapsed; the covering or wall 28 being

omitted. Fig. VIII is an enlarged detail section taken on a line corresponding to the broken line 8—8 of Fig. VII, showing details of the frame structure. Fig. IX is an enlarged detail section taken on a line corresponding to the line 9—9 of Fig. VII, showing the arrangement of the lamp brackets.

In the drawing, similar reference characters refer to similar parts throughout the several views, and the sectional views are taken looking in the direction of the little arrows at the ends of the section lines.

The frame of my improved electric light bath or treatment apparatus, as illustrated in the accompanying drawing to which reference is here made, comprises a pair of side members having upright pieces 1, top horizontal pieces 2, and bottom horizontal pieces 3.

The uprights 1 and the top horizontal pieces 2 are tubular, the tubes being preferably square in section, as illustrated. The top horizontal pieces 2 and the uprights 1 are connected by corner couplings 4 which are hollow to connect the chambers of the pieces 1 and 2.

The uprights and top horizontal members are provided with braces 5, the braces being secured to the members by coupling sleeves 6. The couplings for the outer side members are provided with inwardly-projecting arms 7 to which the transverse connecting members 8 for the side members of the frame are connected by pivots 10.

The corner members of the inner frame side member have arms or hinge members 9 to which the transverse pieces 8 are secured by suitable pivots, as 10.

The arms 7 are provided with braces 11 which are connected to the arms and to the uprights of the outer frame member by suitable coupling sleeves 6.

The bottom horizontal frame pieces 3 are preferably round to adapt them as pivots for the seat cross bar 12. The seat cross bar 12 is provided with diverging or forked extensions 13 at its ends which are secured to the couplings 14 sleeved upon the frame pieces 3 to be slidably adjusted thereon. Collars 15 provided with set screws 30 retain the seat supporting bar in its adjusted positions. The seat 16 is preferably pro-

vided with a screw 17 so that it may be vertically adjusted.

The structure illustrated is adapted for use in connection with a bath tub of common construction, as 18, the inner frame member being secured to the wall at 19 at the side of the tub. Clips 20 are provided for arms attaching the frame to the arms 39 of the wall brackets 32. When 10 the frame is extended, the seat supporting bar rests upon the top of the tub (see Fig. II). When the frame is collapsed, it swings up at the side of the tub as shown in Fig. VII, and a hook 21 is provided for retaining 15 it in its collapsed position.

It is desirable in the use of this apparatus, that the feet of the person being treated, should be in hot water, and by adapting my apparatus for use in connection with a 20 tub, the tub not only serves as a supporting means therefor, but means are provided for supplying the water for the feet while the treatment is being taken. If desired, sufficient hot water may be supplied to the tub to provide a combination steam and light 25 bath. In that case, the feet should be supported as by means of a tub seat. Further, the light treatment is preferably followed with a water bath and the apparatus can 30 be readily swung up out of the way after the light treatment has been completed, to permit the use of the tub.

The lamp brackets 22 are tubular and secured to the uprights 1 by means of the 35 sleeve-like clips 23. The line wires 24 are secured to insulating plates 25, mounted on the top pieces 2, the lamp circuit wires 26 being arranged in the top pieces to extend into the upright pieces 1 through the hollow couplings 4 and into the lamp brackets 22 to the lamps 27. These lamps are of the incandescent type and are provided with reflectors, as illustrated.

The brackets 22 project diagonally from 45 the frame pieces 1, so that the structure may be collapsed without bringing the lamps into contact with any parts of the frame. As the seat is supported directly upon the tub, the frame is subjected to practically no strain, 50 which makes it practical to use a much lighter frame than would be required if the person taking the treatment was to be supported thereby. The lamps being arranged at the corners, direct the light in an effective manner. The number of lamps can be 55 varied as conditions may require.

The lamps are provided with spring contacts so that they may be adjusted in their 60 sockets to bring the reflectors into proper position, but as the structure of these spring contacts is well understood, I do not deem it necessary to illustrate or describe the same herein.

The cover or wall 28 is of suitable flexible 65 material so that the structure may be col-

lapsed without removing the covering. The covering has a suitable head opening 29 in the top, (see Fig. I).

The wall or covering 28 is provided with front and rear flaps 33 and 34, respectively, 70 which depend into the tub to prevent the circulation of air into the cabinet. The side walls are provided with flaps 35 which lap over the edges of the tub to shut out the air at the sides. 75

My improved radiant heat or electric light bath or treatment apparatus is of such simple construction that it can be produced at a reasonable figure, and is very quickly set up for use, and when attached to a wall 80 as shown, is adjustable to its operative or to its inoperative position, merely by swinging it down upon the tub or swinging it against the wall.

I have illustrated and described my improvements in detail in the form in which 85 I have embodied them, as I find that form to be effective for the purpose intended. I desire, however, to remark that very great variation in structural details is possible 90 without departing from my invention, but as the structure illustrated will enable those skilled in the art to which this invention relates, to apply my improvements as circumstances or conditions require, I have not 95 attempted to illustrate or describe the various modifications, but I desire to be understood as claiming the structure specifically 100 in the form illustrated, as well as broadly within the scope of the appended claims. 100

Having thus described my invention, what I claim as new and desire to secure by Letters Patent is:

1. In an apparatus of the class described, the combination of the frame side members 105 each comprising uprights and top and bottom horizontal pieces, said uprights and top pieces being tubular, hollow corner couplings whereby said uprights and top horizontal pieces are rigidly connected, said 110 couplings being provided with inwardly projecting arms, braces for said uprights and top horizontal pieces and said upright and the arms of the couplings of the outer side member, transverse pieces pivotally secured to said inwardly projecting arms of said 115 corner couplings, a seat supporting bar having forked ends mounted on said bottom horizontal pieces to be slidably adjusted thereon, said seat supporting bar being adapted to 120 rest upon a bath tub when the inner side member is secured to the wall at the side thereof, a seat adjustably mounted on said seat supporting bar, a flexible covering for 125 said frame, tubular lamp brackets mounted on said tubular uprights and opening therein, and circuit wires arranged in said horizontal top members and extended into said uprights and said lamp brackets to the lamps carried by said brackets. 130

2. In an apparatus of the class described, a frame comprising tubular side members, a pivotal connection for said side members whereby said frame may be collapsed, said frame being adapted to rest upon the bath tub when the inner side member thereof is secured to the wall at the inner side thereof, a seat support pivotally connected to said side members, a flexible covering for said frame, lamps mounted on said tubular side members, and circuit wires for said lamps arranged in said tubular side members. 5
3. In an apparatus of the class described, the combination of the frame side members each comprising uprights and top and bottom horizontal pieces, said uprights and top pieces being tubular, hollow corner couplings whereby said uprights and top horizontal pieces are rigidly connected, said couplings being provided with inwardly projecting arms, transverse pieces pivotally secured to said inwardly projecting arms of said corner couplings, a seat supporting bar having forked ends mounted on said bottom horizontal pieces, a flexible covering for said frame, tubular lamp brackets mounted on said tubular uprights and opening therein, and circuit wires arranged in said horizontal top members and extended into said uprights and said lamp brackets to the lamps carried by said brackets. 10
4. In an apparatus of the class described, the combination of the frame side members each comprising uprights and top and bottom horizontal pieces, said uprights and top pieces being tubular, hollow corner couplings for said uprights and top horizontal pieces, transverse pieces pivotally secured to said corner couplings, a seat supporting bar mounted on said bottom horizontal pieces to be slidably adjusted thereon, said seat supporting bar being adapted to rest upon a bath tub when the inner side member is secured to the wall at the side thereof, said transverse pieces and seat supporting bar being arranged to permit the collapsing of said frame, a seat adjustably mounted on said seat supporting bar, a suitable covering for said frame, tubular lamp brackets mounted on said tubular uprights and opening therein, and circuit wires arranged in and connected to said horizontal top members and extended into said uprights and said lamp brackets to the lamps carried by said brackets. 15
5. In an apparatus of the class described, the combination of the frame side members each comprising uprights and top and bottom horizontal pieces, said uprights and top pieces being tubular, hollow corner couplings for said uprights and top horizontal pieces, transverse pieces pivotally secured to said corner couplings, a suitable covering for said frame, tubular lamp brackets mounted on said tubular uprights and opening therein, and circuit wires arranged in and connected to said horizontal top members and extended into said uprights and said lamp brackets to the lamps carried by said brackets. 20
6. In an apparatus of the class described, the combination of the frame side members each comprising uprights and top and bottom horizontal pieces, said uprights and top pieces being tubular, transverse pieces pivotally connected to said side members, a seat supporting bar mounted on said bottom horizontal pieces, said seat supporting bar being adapted to rest upon a bath tub when the inner side member is secured to the wall at the side thereof, said transverse pieces and seat supporting bar being arranged to permit the collapsing of said side members, a suitable covering for said frame, tubular lamp brackets mounted on said tubular uprights and opening therein, and circuit wires arranged in said horizontal top members and extended into said uprights and said lamp brackets to the lamps carried by said brackets. 25
7. In an apparatus of the class described, the combination of the frame side members each comprising uprights and top and bottom horizontal pieces, said uprights and top pieces being tubular, transverse pieces pivotally connected to said side members, a suitable covering for said frame, tubular lamp brackets mounted on said tubular uprights and opening therein, and circuit wires arranged in said horizontal top members and extended into said uprights and said lamp brackets to the lamps carried by said brackets. 30
8. In an apparatus of the class described, a frame comprising tubular side members, a pivotal connection for said side members whereby said frame may be collapsed, said frame being adapted to rest upon the bath tub when the inner side member is secured to the wall at the side thereof, a flexible covering for said frame, tubular lamp brackets mounted upon the tubular side members and opening therein, and circuit wires arranged on said tubular side members and extended into said lamp brackets to the lamps carried by the brackets. 35
9. In an apparatus of the class described, the combination of the frame side members each comprising uprights and top and bottom horizontal pieces, couplings whereby said uprights and top horizontal pieces are rigidly connected, said couplings being provided with inwardly projecting arms, braces for said uprights and top horizontal pieces and said upright and the arms of the couplings of the outer side member, transverse pieces pivotally secured to said inwardly projecting arms of said corner couplings, a seat supporting bar having forked ends mounted on said bottom horizontal pieces to 40

be slidably adjusted thereon, said seat supporting bar being adapted to rest upon a bath tub when the inner side member is secured to the wall at the side thereof, a seat 5 adjustably mounted on said seat supporting bar, a flexible covering for said frame, and lamps mounted on said side members.

10. In an apparatus of the class described, the combination of the frame side members each comprising uprights and top and bottom horizontal pieces, couplings whereby said uprights and top horizontal pieces are rigidly connected, said couplings being provided with inwardly projecting arms, braces 15 for said uprights and top horizontal pieces and said upright and the arms of the couplings of the outer side member, transverse pieces pivotally secured to said inwardly projecting arms of said corner couplings, a flexible covering for said frame, and lamps 20 mounted on said side members.

11. In an apparatus of the class described, the combination of the frame side members each comprising uprights and top and bottom horizontal pieces, transverse pieces pivotally connected to said side members, a seat supporting bar mounted on said bottom horizontal pieces to be slidably adjusted thereon, said seat supporting bar being 30 adapted to rest upon a bath tub when the inner side member is secured to the wall at the side thereof and being arranged to permit the collapsing of said frame, a seat adjustably mounted on said seat supporting 35 bar, a flexible covering for said frame, and lamps mounted on said side members.

12. In an apparatus of the class described, the combination of the frame side members each comprising uprights and top and bottom horizontal pieces, transverse pieces pivotally connected to said side members, a seat supporting bar mounted on said bottom horizontal pieces, said seat supporting bar being adapted to rest upon a bath tub when 40 the inner side member is secured to the wall at the side thereof and being arranged to permit the collapsing of said frame, a seat mounted on said seat supporting bar, a flexible covering for said frame, and lamps 45 mounted on said side members.

13. In an apparatus of the class described, a frame comprising side members, a pivotal connection for said side members whereby said frame may be collapsed, said frame being adapted to rest upon a bath tub when the inner side member is secured to the wall at the side thereof, a flexible covering for 55 said frame, and lamps mounted on said side members of said frame.

60 14. In an apparatus of the class described, the combination with a bath tub of a collapsible frame comprising side members and transverse frame members pivotally connected to said side members, brackets for 65 attaching one of said frame side members

to the wall at the side of the bath tub whereby the frame may be collapsed against the wall or extended to rest upon the bath tub, and a flexible covering for said frame provided with extensions or flaps on its front 70 and rear walls adapted to depend into the bath tub.

15. In an apparatus of the class described, the combination with a bath tub, of a collapsible frame comprising side members 75 and transverse frame members pivotally connected to said side members, brackets for attaching one of said frame side members to the wall at the side of the bath tub whereby the frame may be collapsed against the 80 wall or extended to rest upon the bath tub, and a flexible covering for said frame provided with flaps or extensions on its walls adapted to depend into the bath tub, for the 85 purpose specified.

16. In an apparatus of the class described, the combination of a collapsible frame comprising side frame members, each frame member comprising upright and top and bottom pieces; top transverse pieces pivotally mounted on the outer sides of the uprights; a seat supporting bar pivotally mounted on the bottom pieces of said side frame members between their uprights so that the outer frame member may be swung 95 up to the wall to collapse the structure; a wall attaching bracket for one of said frame members; a seat on said bar; and lamps mounted on the uprights of said frame members, the supporting brackets for the lamps 100 being disposed so that the lamps carried by the outer frame member collapse between the top transverse pieces and the seat collapses between the uprights of the inner frame member and the lamps mounted 105 thereon.

17. In an apparatus of the class described, the combination of a collapsible frame comprising side frame members, each frame member comprising upright and top and bottom pieces; top transverse pieces pivotally connected to said members; a seat supporting bar pivotally mounted on the bottom pieces of said frame members between their uprights so that one frame member 110 may be collapsed upon the other; and lamps mounted on the uprights of said frame members, the lamps being disposed so that the lamps carried by the swinging frame member collapse between the top transverse 115 pieces and the seat bar collapses between the uprights of the other frame member and the lamps mounted thereon.

18. In an apparatus of the class described, the combination of a collapsible frame comprising side members; wall attaching brackets for one of said frame side members; pivotal connections for the other frame side member to the side member attached to the wall, whereby such member may be swung 125 130

up to the wall when the structure is collapsed; a flexible covering for said frames; and lamps mounted on the side members of said frame.

- 5 19. In an apparatus of the class described, the combination of a collapsible frame comprising side frame members; a wall attaching bracket for one of said side frame members; link connections for the other side frame member to the member provided with the wall attaching brackets, whereby the swinging frame member may be swung up to the wall to collapse the frame; and lamps carried by said side members, the lamps and frame links being disposed so as to permit them to swing past each other when the structure is collapsed.
- 10 20. In an apparatus of the class described, the combination of a collapsible frame comprising side frame members; links pivotally secured to said frame members to permit
- 15
- 20

one of the frame members being swung on the links to collapse the frame; and lamps carried by said frame members, the lamps and links being disposed so as to permit them to swing past each other when the frame is collapsed.

21. In an apparatus of the class described, the combination of a collapsible frame comprising side members, said frame being adapted to be extended to rest upon a bath tub when its inner side member is secured to the wall at the side of the tub or to collapse against the wall; and lamps mounted upon the side members of said frame. 35

In witness whereof, I have hereunto set my hand and seal in the presence of two witnesses:

ROY X. TUTTLE. [L.S.]
